UNITED STATES PATENT OFFICE.

ARBY W. BAILEY, OF IRON RIVER, WISCONSIN.

RAILROAD GATE.

Application filed November 18, 1924. Serial No. 750,687.

To all whom it may concern:

Be it known that I, ARBY W. BAILEY, a citizen of the United States, residing at Iron River, in the county of Bayfield and State 5 of Wisconsin, have invented certain new and useful Improvements in Railroad Gates, of which the following is a specification.

This invention relates to gates for railroad crossings and has for its object the provision of means whereby, when a train is approaching a crossing, a barrier will be disposed across the road to bar the entrance of pedestrians or vehicles upon the railroad track and will be automatically removed as 10 the train passes beyond the crossing. The invention seeks to provide a gate which will be normally held in open or raised position and means whereby, when a train is approaching the crossing, the gate will be automatically lowered and will be automatically raised as the train passes beyond the crossing. The invention also seeks to provide such an automatically operated gate or barrier in which the working parts will be simple in arrangement and, therefore, not apt 15 to get out of order and which will be so arranged as to be operated under all conditions. The invention is illustrated in the accompanying drawings and will be hereinafter fully set forth.

In the drawings:

Figure 1 is a side elevation of a railroad gate embodying my improvements;

Fig. 2 is a plan view of the same;

Fig. 3 is an enlarged horizontal section on the line 3—3 of Fig. 1, and

Fig. 4 is a vertical section on the line 4—4 of Fig. 3.

In the drawings, the reference numeral 1 indicates a portion of a railroad track of the usual construction, and 2 indicates a portion of a road crossing the track. In carrying out my invention, I erect a post 3 adjacent the side of the crossing and adjacent 45 the track so that a swinging bar or gate 4 mounted upon the post will extend parallel with the track and when lowered will project over the crossing. This post may be anchored in any convenient manner and the 50 bar or gate 4 is pivotally supported in a bracket 5 secured on the side of the post, a counter-weight 6 being secured upon the shorter arm of the gate, as shown. This weight should be of such size as to normally hold the gate in raised position so that, 55 when the forces operating to lower the gate

are removed, the gate will be automatically raised. Mounted in any convenient manner upon the post is a guide pulley 7 and a cable 8 extends around the said guide pulley and 60 is secured to the gate, as clearly shown. The pulley 7 may be protected against the weather by any convenient form of housing, but such housing has not been shown in the drawings in order to more clearly illustrate 65 the working parts. From the pulley 7, the cable 8 extends away from the crossing parallel with the track and is supported in guide posts 9 in a well-known manner. The remote end of the cable passes into a housing 10 which is preferably in the form of a cylindrical tube provided with side flanges or similar members 11 through which fastening devices are inserted to anchor the housing upon extensions of the railroad ties. 70 Within the housing 10 is a slide or cross-head 12 which may conveniently be a circular disk of any material possessing the requisite strength. The end of the cable 8 is attached to the disk by engagement with 75 a hook or eye 13 disposed centrally of the disk and firmly united therewith. At the opposite side of the disk is a loop or eye 14 in which is engaged one end of a coiled tension spring 15 which extends to the opposite 80 end of the housing and is there secured by engagement with a hook or staple 16 firmly secured in the housing, as shown most clearly in Fig. 3. Obviously, the spring 15 tends 85 constantly to contract and thereby exerts a 90 pull upon the cable which tends to lower the gate. The spring is normally held extended so that the gate will be in raised position by 95 dogs or restraining levers 17 mounted upon opposite sides of the housing 10 and ar- 95 ranged to be operated by a passing train. These levers, as clearly shown in Fig. 3, are fulcrumed between their ends upon lugs or brackets 18 formed upon the sides of the housing, and expansion springs 19 are dis- 100 posed between the housing and the levers to hold them normally in working position. The heads or working ends of the levers are provided with lugs or hooks 20 which are 105 adapted to engage against the crosshead or slide 12 and thereby hold the same against the force of the spring 15, as will be readily understood upon reference to Fig. 3, slots 21 being provided in the sides of the housing to permit the lugs or hooks 20 to pass 110 into the housing and assume their working positions in engagement with the crosshead.

A link 22 extends over the housing 10 and has one end pivotally engaged in the working end of that lever which is nearer the track and its opposite end engaged in the 5 free end of the more remote lever so that, when the first-mentioned lever is rocked, the remote lever will be likewise rocked and the crosshead released so that it may move under the influence of the spring and will 10 pull upon the cable 8 so as to lower the gate. Between the track and the adjacent lever, I provide a rocking arm or trip lever 23 which preferably has its two arms disposed at an angle to each other and is fulcrumed 15 at its angle, as shown at 24. The longer arm of this lever terminates near the track in position to be struck by a striker arm of any desired form mounted upon a locomotive and it is normally held in this position by a 20 contractile spring 25 attached to the lever and a fixed element 26 of any approved type. Adjacent the longer arm of the lever is a stop 27 which limits the movement of the lever under the influence of the spring 25 so 25 that it cannot assume an inoperative position. The shorter arm of this trip lever carries a roller 28 which is adapted to ride upon the free end of the adjacent lever 17 and the parts are so proportioned and ar- 30 ranged that the arc described by this roller or the free end of the trip lever will intersect the vertical plane of the adjacent surface of the lever 17 so that, when the trip lever is rocked, the free end of the lever 17 35 will be swung toward the housing 10 and the head or lug 20 released from the crosshead 12, a like movement of the remote lever 17 being effected through the link 22. When the crosshead 12 is thus released, the spring 40 15 at once contracts and the gate is lowered.

Near the post 3, I provide a housing 29 in which is mounted a guide roller 30 and adjacent the said housing is mounted a trip arm 31 which has one end disposed in the 45 path of the striker arm upon an oncoming locomotive and its opposite end attached to a short cable 32 which passes forwardly from the lever and around the roller 30 and then rearwardly to be connected with the 50 main operating cable 8. The lever 31, as shown clearly in Figs. 1 and 2, is disposed near the crossing and, when it is struck by a locomotive, it will exert a pull through the auxiliary cable 32 upon the main cable 8 55 so as to impart reverse movement to the said main cable 8 and permit the gate to rise under the influence of the weight 6. Of course, when the trip lever 23 has been freed of the locomotive or the striker thereon, the 60 springs 19 and 25 at once return it and the levers 17 to their normal working positions with the lugs or heads 20 projecting into the housing 10. To prevent the said lugs stopping the crosshead 12 before the gate is 65 fully raised, the edges of said lugs presented

toward the spring 15 are beveled so that, when the crosshead or slide returns to its initial position, it may easily push the lugs aside so as to resume its position in engagement with the abrupt faces of the same. 70

From the foregoing description, taken in connection with the accompanying drawings, it will be seen that I have provided a simple and compact mechanism which will be automatically actuated by a train approaching the crossing so that a barrier will be automatically disposed across the road at the side of the railroad track and will remain in that position until the train is passing over the crossing when it will be automatically released and permitted to rise. It will, of course, be understood that the gate or barrier may be provided at each side of the track and at each side of the crossing and that the plurality of gates so provided 80 may be connected through suitable gearing to be controlled and operated simultaneously whenever a train approaches in either direction. Such variations, however, are not 85 illustrated as they involve merely duplication of the parts shown and described and will readily occur to skilled mechanics. 90

It will be understood that the working parts, in actual practice, are all enclosed so as to be protected from the elements, only 95 the working ends of the levers being exposed. It will also be understood that at night a lantern will be hung upon the gate.

Having thus described the invention, I 100 claim:

1. An apparatus for the purpose set forth comprising a gate mounted to be raised and lowered and normally held in a raised position, a crosshead, a cable secured to and extending between the crosshead and the 105 gate, a spring attached to the crosshead and tending constantly to move the same away from the gate whereby to lower the gate, a dog normally engaging the crosshead and restraining the action of the spring, and means whereby the dog will be released from the crosshead by a passing train to permit lowering of the gate.

2. An apparatus for the purpose set forth comprising a gate mounted to be raised and lowered, a contractile spring, a crosshead attached to said spring, a cable attached to said crosshead and the gate, dogs engaging the crosshead and normally restraining the same against movement under the influence of the spring, a connection between said dogs whereby to cause simultaneous movement of the same in opposite directions, and a trip arm mounted adjacent one of said dogs and bearing against the same and arranged to be actuated by a passing train whereby to release the dogs from the crosshead and permit lowering of the gate under the influence of the spring. 110 120 125

3. An apparatus for the purpose set forth 130

comprising a gate mounted to be raised and lowered, a slideable crosshead, a cable connecting the crosshead with the gate, a contractile spring connected with the crosshead and tending constantly to lower the gate, means engaging the crosshead to prevent its movement under the influence of the spring, means to be actuated by a passing train to release the dogs from the crosshead, a trip arm arranged adjacent the gate to be actuated by a passing train, a guide arranged between said trip arm and the gate, and a branch cable connected to said trip arm and to the first-mentioned cable and passing around the guide whereby upon actuation of said trip arm a reverse movement will be imparted to the first-mentioned cable. 15

In testimony whereof I affix my signature.

ARBY W. BAILEY. [L. s.]
